UNITED STATES PATENT OFFICE.

WALTER S. RAGSDALE, OF NEW YORK, N. Y.

DESIGN FOR A FLAG.

60,813.

Specification for Design.

Patented Apr. 11, 1922.

Application filed May 24, 1920. Serial No. 383,995. Term of patent 3½ years.

To all whom it may concern:

Be it known that I, WALTER S. RAGSDALE, citizen of the United States, residing at New York city, in the county of New York and State of New York, have invented a new, original, and ornamental Design for Flags, of which the following is a specification, reference being had to the accompanying drawings, forming part thereof, in which the figure is a view in elevation of a flag showing my new design.

The design consists of a field of seven horizontal red stripes and six horizontal white stripes, alternately arranged, a circular insert being provided at one end of the field which is limited and defined by a cord having its end tied with a bow-knot and the terminals tasseled. The flag is surround-

ed on three sides by a border, omitting the same from the side adjacent the flag staff as shown. The insert is blue and provided with a central relatively large white star and surrounded by six circumferentially arranged white stars of lesser magnitude and said last mentioned stars surrounded by an annular series of twelve white stars of still lesser magnitude.

I claim:

The ornamental design for a flag as shown.

In testimony whereof I affix my signature in presence of two witnesses.

WALTER S. RAGSDALE.

Witnesses:

STEFANO BURGIO,
GIUSEPPE PACINI.
